Atty's.

UNITED STATES PATENT OFFICE

LEONARD A. MACLEAN, OF READING, MASSACHUSETTS

PATCH-APPLYING IMPLEMENT

Application filed January 9, 1930. Serial No. 419,582.

The object of this invention is to provide a compact and conveniently operable implement resembling a hand stamp in that it includes a base or bed and a plunger, adapted to be manually projected toward the bed and automatically retracted therefrom like the plunger of a hand stamp, the bed being adapted to support a paper article such as a tag or a leaf for a loose-leaf binder, and the plunger being adapted to apply gummed reinforcing patches, one at a time, to articles successively placed on the bed, the patches surrounding holes in the articles to which they are applied.

15 A particular object of the invention is to provide means for connecting a charge of patches with the plunger in such manner that the patches may be applied successively until the charge is exhausted, the connecting means 20 being removable from the plunger and adapted to be provided, when removed, with another charge.

Of the accompanying drawings forming a part of this specification,—

25 Figure 1 is a perspective view of an implement embodying the invention, the plunger being retracted.

Figure 2 is a sectional view, showing a fragment of the base, the plunger being retracted.

30 Figure 3 is a view similar to a portion of Figure 2, showing the plunger partly projected.

Figure 4 is a side view of a tag having a 35 reinforcing patch.

Figure 5 is a section on line 5—5 of Figure 4.

Figure 6 is a fragmentary sectional view, showing an end portion of the plunger.

40 Figures 7, 8 and 9 are side views of parts shown in section by Figure 2.

Figure 10 is an enlargement of a portion of Figure 2.

Figure 11 is a view similar to Figure 2, 45 showing the plunger fully projected.

Figures 12 and 13 are detail views, showing a modification.

The same reference characters indicate the same parts in all of the figures.

50 In the drawings, 15 designates a bed adapt-

ed to support a tag 16 or other like article having a hole 17.

18 designates a tubular plunger provided at one end with an annular pressing face 19. The plunger is guided in a predetermined path toward and from the bed by a guide 20, forming a part of a bracket fixed to the bed. The plunger is adapted to be manually projected toward the bed and is normally retracted by a spring 21 interposed, in this instance, between a fixed abutment 22 in the bore of the plunger and a head 23 fixed to the upper end of the plunger, the abutment 22 being fixed to the guide 20 by clamping screws 24 engaged with the guide and with opposite sides of the abutment. The screws pass through longitudinal slots 180 in opposite sides of the plunger.

25 designates a cylindrical core whereon a plurality of annular gummed reinforcing patches 26 may be strung in contact with each other to form a cylindrical body or charge from which the patches may be detached or dispensed one at a time. The core is preferably a short length of brass tubing 70 of a suitable diameter to permit the patches to slide freely on to one of its ends and toward its delivering end which is the lower end in Figure 2. Said delivering end has an enlargement 27 (Figure 10) formed to releasably engage an end patch 26 and support the charge in contact with the pressing face 19 of the plunger. Said enlargement is preferably a very narrow outwardly projecting flange or bur formed on the end of the 75 core, and adapted to prevent accidental removal from the core of an end patch bearing on the enlargement, so that the enlargement prevents the charge from dropping from the core when the latter is in a vertical position.

The enlargement is also adapted to permit the removal from the core of a patch which has been applied to an article 16, as herein-after described.

80 The core 25 is slidable longitudinally in the bore of the tubular plunger, so that it may be telescoped therein as indicated by Figure 11, to conform to any decrease in the length 85 of the charge and maintain one end of the 90 100

charge in contact with the pressing face of the plunger.

I provide frictional retaining means adapted to releasably maintain the core in any position to which it is slidable in the plunger and permit the removal of the core from the plunger after a charge has been exhausted, so that the core may be recharged. I embody the preferred frictional retaining means in a cylindrical plug or slide 29, located loosely in the plunger core between the abutment 22 and an internal stop shoulder 30 on the plunger, and a stud 31 projecting from the slide and adapted to enter and frictionally engage the upper end portion of the core, said end portion being split by a slot or slots 32, so that it is adapted to hug the stud. When the plunger is fully retracted the slide 29 is rigidly backed by the abutment 22, as shown by Figure 2, so that the split end of the core may be forced upon the stud and frictionally engaged therewith, the slide and stud being supported by the stop shoulder 30, so that the core may be removed from the plunger by pulling it downward from the stud. The alternative frictional retaining means shown by Figures 12 and 13 is provided by a split ring 33 confined in the plunger bore between stop shoulders 34 and adapted to yieldingly embrace the core 25, the core being slidable in and removable from the ring 33.

The bed 15 is provided with an upwardly projecting boss 35, formed to enter a hole 17 in an article 16 placed on the bed and located in alignment with the core 25.

The implement is prepared for operation by stringing patches on the core to form a suitable charge; then engaging the core as described with the plunger while the latter is retracted, one end of the charge being maintained in contact with the pressing face 19 of the plunger. A portion of an article 15 surrounding the hole 16 is then moistened, and the article is deposited on the bed with its moistened portion facing upward. The plunger is then manually projected until the releasably confined end patch is applied to the moistened portion of the article, the gummed surfaces of the patches facing downward, so that the applied patch adheres to the article. The plunger is then released and retracted. The adhesion of the applied patch to the article, and the described form of the end enlargement of the core enables said patch to be separated from the core without being detached from the article, the next patch of the charge becoming an end patch which is releasably arrested by the end enlargement of the core and adapted to be applied to an article on the bed.

As shown by Figure 11, the core may be telescoped into the plunger until the last patch of the charge is applied.

It will be seen that the implement may be

rapidly operated, each projection of the plunger applying a patch to an article.

The implement may constitute a simple and inexpensive part of the equipment of a job printing establishment, enabling the printer to patch tags or leaves printed in the establishment, without the delay often involved in procuring blank patched tags or leaves from another manufacturer.

The bed 15 may be the cover of a hollow base portion 37. Gage members 39 may be secured to the bed in position to cooperate with the boss 35 in locating an article on the bed.

I claim:—

1. A patch-applying implement comprising an article-supporting bed, a tubular plunger provided at one end with a pressing face, means for guiding the plunger in a predetermined path toward and from the bed, means normally retracting the plunger, and a core whereon a plurality of annular gummed patches may be strung to form a charge from which patches may be dispensed singly, said core having at its delivering end an enlargement formed to releasably engage an end patch and support the charge in contact with the pressing face, the core being slidable in the plunger so that it may be telescoped therein to conform to any decrease in the length of the charge and maintain the latter in contact with the pressing face, frictional means being provided adapted to releasably maintain the core in any position to which it is slidable, and permit the removal of the core from the plunger for recharging, the arrangement being such that the projection of the plunger applies the gummed face of an end patch to an article on the bed, and causes the adhesion of said patch to a moistened surface of the article, the end enlargement of the core being formed to permit the separation of the applied patch and the article from the charge when the plunger is retracted.

2. A patch-applying implement as specified by claim 1, the said plunger-guiding means being embodied in a fixed guide surrounding the plunger, a spring abutment fixed to the guide by fastening members engaged with the guide and extending through longitudinal slots in the plunger, and a retracting spring interposed between said abutment and a head on the plunger, the said frictional means including a slide movable in the plunger below said abutment and provided with a stud formed to enter and frictionally engage an end portion of the core, said end portion being separable from the stud, the slide being maintained in contact with said abutment when the plunger is retracted, so that the stud is supported to permit the frictional engagement of the core therewith.

3. A patch-applying implement as specified by claim 1, the bed being provided with

a boss located in alignment with the core and adapted to enter a hole in an article placed on the bed and locate said article in position to cause an applied patch to surround the hole.

5 4. A patch-applying implement of the hand stamp type, comprising a bed, a tubular plunger provided with a pressing face and guided in a predetermined path toward
10 and from the bed, and a core whereon a plurality of annular patches may be strung to form a charge whose members are releasably confined on the core, said core being aligned with the plunger, separably engaged therewith to permit renewal of a charge, and slideable in the plunger to maintain the charge in contact with the pressing face.

In testimony whereof I have affixed my signature.
